UNITED STATES PATENT OFFICE.

WILLIAM JAMES BURROUGHES AND WILLIAM JAMES BURROUGHES, JR., OF LONDON, ENGLAND.

RADIATOR FOR HEATING APPARATUS.

No. 855,692.

Specification of Letters Patent.

Patented June 4, 1907.

Application filed August 24, 1906. Serial No. 331,912.

To all whom it may concern:

Be it known that we, WILLIAM JAMES BURROUGHES and WILLIAM JAMES BURROUGHES, Jr., subjects of the King of Great Britain, residing at 143 Queen Victoria street, London, England, have invented new and useful Improvements in Radiators for Heating Apparatus, of which the following is a specification.

Our invention relates to radiators of the kind used in connection with apparatus for heating buildings by means of hot water or steam.

Heretofore it has been a frequent custom to apply upon a radiator a reservoir or tray for containing water which is gradually evaporated by the heat emitted from the radiator so as to moisten the air. This arrangement, however, is more or less unsightly and, furthermore, the evaporation is usually very slow.

According to our invention we form the radiator coils with openings or recesses to permit of a tray being inserted through the radiator, which tray will thus not only be practically concealed from view but will also be so surrounded by the coils and in such close contact therewith that a relatively rapid evaporation of the water therein will take place.

To enable our invention to be fully understood we will describe the same by reference to the accompanying drawings, in which:

Figure 1 is a sectional front elevation, and Fig. 2 an end elevation partly in section of a radiator provided with our invention.

a, a are the coils or sections of the radiator, each of which, as shown, is provided with an aperture *b*, which apertures, when a number of sections are bolted together, form a recess for receiving a water tank *c*, which water tank is advantageously in the form of a drawer which extends through the radiator, as shown in Fig. 1. It will be no-

ticed that this drawer although constructed to permit a large volume of vapor to rise 45 therefrom is only visible between the sections of the radiator, so that its presence is not unsightly and also that it is more or less in close contact with the radiator coils, so that rapid evaporation can take place. 50

Although in the drawing we have represented the drawer as being applied to radiator sections having triple passages, it is to be understood that the invention is equally applicable to radiators having only twin 55 passages or to any other form of radiator. It is also to be understood that the water tank or drawer, instead of being placed near the upper part of the coils, may be placed at the lower part thereof or at any intermediate position and that the drawer, instead of being of rectangular section, may be of circular, oval or any other desirable form.

Having now particularly described and ascertained the nature of our said invention 65 and in what manner the same is to be performed, we declare that what we claim is:

The combination with a radiator comprising a series of vertically disposed flat sections arranged side by side, certain of 70 said sections adjacent to one another being provided with horizontally alined openings extending therethrough, of a receptacle fitting within said openings in said sections, said sections being so arranged that said 75 receptacle may be inserted and withdrawn through the section at one end of the radiator while a section at the inner end of said receptacle forms a stop therefor, substantially as described.

WILLIAM JAMES BURROUGHES.
WILLIAM JAMES BURROUGHES, JR.
